Specification for Design.

Patented Nov. 30, 1920.

Application filed April 30, 1920. Serial No. 378,024. Term of patent 14 years.

To all whom it may concern:

Be it known that I, CHARLES H. NEWTON, a citizen of the United States, residing at Plainville, in the county of Hartford and State of Connecticut, have invented a new, original, and ornamental Design for Valve-Spring Compressors, of which the following is a specification, reference being made to the accompanying drawings, forming part thereof.

In the drawings Figure 1 is a plan view, and Fig. 2 is a side view of a valve spring compressor embodying my design.

I claim:

The ornamental design for a valve spring compressor as shown.

CHARLES H. NEWTON.
